US0D1061510S

(12) **United States Design Patent** (10) Patent No.: **US D1,061,510 S**
(45) Date of Patent: ** *Feb. 11, 2025

(54) **ELECTRONIC DEVICE**

- (71) Applicant: **Samsung Electronics Co., Ltd.**, Suwon-si (KR)
- (72) Inventors: **Jaewoong Chung**, Suwon-si (KR); **Duyeong Choi**, Suwon-si (KR); **Seonkeun Park**, Suwon-si (KR); **Ethan Lee**, Suwon-si (KR); **Jungwon Lee**, Suwon-si (KR); **Seungjoon Lee**, Suwon-si (KR)
- (73) Assignee: **SAMSUNG ELECTRONICS CO., LTD.**, Suwon-si (KR)

(*) Notice: This patent is subject to a terminal disclaimer.

(**) Term: **15 Years**

(21) Appl. No.: **29/906,873**

(22) Filed: **Nov. 13, 2023**

(57)

CLAIM

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The dashed broken lines in the figures illustrate portions of the electronic device that form no part of the claimed design.

(Continued)

The dot-dash broken lines in the drawings define the boundaries of the claimed design and form no part thereof.

1 Claim, 6 Drawing Sheets
